(57) **CLAIM**

I claim the ornamental design for a hearing assistance device, as shown and described.

DESCRIPTION

FIG. 1 is a front perspective view of a hearing assistance device of the present invention;

FIG. 2 is a front elevation view of the hearing assistance device of FIG. 1;

FIG. 3 is a rear elevation view of the hearing assistance device of FIG. 1;

FIG. 4 is a left side elevation view of the hearing assistance device of FIG. 1;

FIG. 5 is a right side elevation view of the hearing assistance device of FIG. 1;

FIG. 6 is a top plan view of the hearing assistance device of FIG. 1; and,

FIG. 7 is a bottom plan view of the hearing assistance device of FIG. 1.

The broken lines shown are for illustrative purposes only and form no part of the claimed design.
